BED MOTION

James R. Wood, Shelton, Conn., assignor to Harris-Seybold-Potter Company, Cleveland, Ohio, a corporation of Delaware

Application July 8, 1936, Serial No. 89,615

21 Claims. (Cl. 74—27)

This invention relates to improvements in bed reversing mechanism, that is mechanism for reversing the movement of the bed of a flat bed printing press at the ends of its stroke. In a printing press of this character the reciprocating bed is given a constant speed motion throughout the greater portion of its travel in each direction, but at the two ends of the stroke it is slowed down to a stop and started in the other direction with an accelerating motion. This reversal of motion approximates more or less closely a simple harmonic motion. The present invention has to do primarily with novel and effective means for imparting such reversing motion to the bed of a flat bed press, although the invention is susceptible of use in connection with other machines in which there are reciprocating parts or parts oscillating about an axis.

One of the objects of the invention is the provision of simple and relatively inexpensive mechanism for the purpose stated, which shall be effective and smooth in operation.

Other objects and features of novelty will appear as I proceed with the description of those embodiments of the invention which, for the purposes of the present application, I have illustrated in the accompanying drawings, in which

Fig. 1 is an elevational side view showing in a somewhat diagrammatic manner the bed driving mechanism of a flat bed printing press embodying the invention.

Fig. 2 is a detail plan view of the bed rack and driving pinion.

Fig. 3 is a view similar to Fig. 1, but on a smaller scale, showing the mechanism in a position which it occupies during the reversing operation.

Fig. 4 is a view similar to Fig. 1 illustrating a modification.

Fig. 5 is a plan view of the bed rack and reversing rack of Fig. 4.

Fig. 6 is a side elevation of still another modification.

Fig. 7 is a plan view of the bed rack and pinions of Fig. 6, and

Fig. 8 is a vertical cross sectional view taken substantially on the line 8—8 of Fig. 1.

Referring first to Figs. 1, 2, 3 and 8, I have shown a shaft 10 to which driving force is delivered by any suitable means. On the shaft 10 there is a gear 12 which meshes with a large gear 13, the latter gear having a diameter preferably three times that of gear 12. The large gear carries a gear segment 14 with internal gear teeth and a gear segment 15 with external teeth.

Each of these segments occupies an angle of approximately 120°, and they are positioned diametrically opposite each other. Internal gear segment 14 is adapted to mesh with a pinion 16, and the external gear segment 15 with a pinion 17. These two pinions are keyed to a shaft 18 which extends transversely across the machine and carries about midway between the frame members a pinion 19 which meshes with teeth on the under side of a bed rack 20.

In the machine between the frame members there is mounted a longitudinally extending guide rail 21 upon which is mounted a slide 22 having a vertical guide 23 forming part of a Scotch yoke construction. The other part of this yoke consists of a crank roller 24 which is journaled upon a disk 25 keyed to shaft 10. The slide 22 therefore is given a simple harmonic motion, and because of the relation between gears 12 and 13 there are three reciprocations of slide 22 for each rotation of the large gear 13. Also, since gear 13 makes one revolution for each complete reciprocation of the bed of the press, there are three reciprocations of slide 22 for each reciprocation of the bed.

To the forward end of slide 22 there is pivoted a rack 26 having teeth on its upper surface adapted to mesh with the teeth of pinion 19. The forward end of this rack runs upon and is supported by a wheel or roller 27, which turns upon a shaft 28 that is carried in the free end of a bifurcated link 29 which is pivotally supported at 30 in the frame of the machine. Shaft 28 also carries on opposite sides of wheel 27 two smaller wheels 31 which constitute followers for a bifurcated cam 32 pivoted at 33 on the frame of the machine. In the position of cam 32 illustrated in Figs. 1 and 8 of the drawings the rack 26 runs upon roller 27 out of contact with pinion 19. When the cam 32 is in the position illustrated in Fig. 3 however the roller 27 holds the reciprocating rack 26 in mesh with pinion 19, and motion is transmitted to the bed 34 of the machine from the reciprocating rack.

Cam 32 is formed integral with an arm 35 which extends downwardly below pivot 33 where it is connected with a link 36, the opposite end of which is pivotally connected with an arm 37 which swings upon a pivot 38 supported in the frame. The upper end of arm 37 carries a roller follower 39 which runs upon a cam 40 that is keyed to a shaft 41. Shaft 41 is driven from shaft 10 by means of intermeshing gears 42 and 43 mounted upon those shafts. The gear ratio is such that gear 41 turns at one-third the speed of gear 10.

of shaft 10, and therefore at the same rate as gear 13. In other words it makes one revolution for each complete reciprocation of the bed. There are two high spots on cam 40 however, and hence 5 roller 21 is raised twice for each reciprocation of the bed, the timing being such that this action occurs at the ends of the bed stroke. One engagement of the rack 26 with pinion 19 occurs while the roller 24 of the Scotch yoke is moving 10 from top position to lowermost position, and the other engagement of the rack with the pinion occurs while the roller 24 is moving from lowermost position up to top position, a full rotation of shaft 10 having intervened during which the rack 15 is out of engagement with the pinion.

In the form of the invention illustrated in Figs. 4 and 5 there are two racks on the bed of the machine, a constant speed rack 44 and a reversing rack 45. The pinion 19 meshes with the rack 10 44. Reversing rack 45 meshes continuously with a pinion 46 carried by shaft 47 supported in the machine frame. The reciprocating rack 26 is arranged beneath pinion 46, and is lifted at the proper times to mesh with the pinion in the same manner as in the previously described form of the invention.

The modification of Figs. 6 and 7 in a sense combines certain features of the two previously 30 described forms, that is to say it employs a separate reversing pinion 48 as in Fig. 4, and a single bed rack as in Fig. 1. The pinion 19 and the pinion 48 are both continuously in mesh with the single bed rack 49. Pinion 48 is engaged periodically by reciprocating rack 26 in the same 35 manner as previously described.

Operation.—The shafts 10 and 41 and the gears 12, 13 and 43 rotate continuously in the directions indicated by the arrows in Figs. 1 and 4. In 40 both of these figures the bed is shown moving toward the right in the constant speed portion of its travel. This constant speed motion is imparted to the bed by the rotation of shaft 18 in a clockwise direction through the operation of gear segment 15 and pinion 17. During this time the 45 rack 26 is reciprocating in its lowered position. In the case of Fig. 4 the pinion 46 is being driven by the rack 45.

At the point where segment 15 leaves pinion 17 roller 24 is at its lowermost position. The rack 50 is raised at that point and meshes with pinion 19. It is then moving toward the left at maximum speed, and hence meshes with pinion 19 without clash. Its speed steadily decreases thereafter through the next quarter revolution of shaft 10, 55 reaching zero at the end of the quarter revolution. The following quarter revolution accelerates the rack 26 from zero speed to maximum speed in the direction toward the right, which likewise reverses the rotation of pinion 19, and likewise the 60 direction of movement of bed 34. When roller 24 reaches its top position the rack 26 is lowered, and at the same time segment 14 comes into mesh with pinion 16 and the constant speed travel of the bed in the direction toward the left is begun. 65 In the case of Fig. 4, while the reversing action is taking place shaft 18 is slowed down, reversed and accelerated because of the continuous meshing of pinion 19 with bed rack 44, so that when segment 14 comes into meshing position the pinion 16 is traveling at the same surface speed as segment 14. The reversing motion in Fig. 4 is 70 accomplished in the same manner as in Fig. 1, except that a separate bed rack and pinion 45 and 46 are used for the purpose.

75 When segment 14 goes out of mesh with pinion

16 the bed is at the end of the constant speed travel toward the left. At this point crank roller 24 is at the top of its circle of rotation and moving at maximum speed corresponding to the constant speed motion of the pinion 19. At this point 5 the reciprocating rack 26 is raised into mesh with the pinion. It is moving toward the right at the time. As the roller 24 moves down clockwise its speed is decelerated, and the speed of rack 26 is correspondingly decelerated. At the first quarter position, 90° from the top, the travel of slide 22 and rack 26 is at zero rate, and motion of the rack in the opposite direction begins, thereby reversing the direction of motion of the bed. As 10 previously stated, each of the segments 14 and 15 occupies an angle of 120°. There are two angles of 60° between the segments during which the reversing mechanism functions. It may also be noted, as of some importance, that the bed is balanced more or less against the slide 22 and the 15 rack 26, that is to say at the times of reversal of bed motion the momentum of the bed is opposed by that of slide 22 and rack 26. This arrangement assists in cutting down vibration to a minimum.

The operation of the construction illustrated in 20 Figs. 6 and 7 does not differ substantially from that illustrated in Figs. 4 and 5, and further explanation is therefore unnecessary. In both of these cases the drive to the bed at constant speed 25 is different from that of reversal, the pinions 46 and 48 transmitting no force to the bed at constant speed, and the pinions 19 transmitting none at reversal. When one of the pinions 19 and 46 is transmitting force to the bed, the other pinion 30 46 is being driven by the bed. In Fig. 1 on the other hand the pinion 19 acts to drive the bed at all times, the shaft 18 being driven by the 35 reversing mechanism as well as by the constant speed mechanism.

Variations from the described structure may be 40 employed. Accordingly I desire it to be understood that the scope of the invention is to be regarded as defined exclusively by the appended claims rather than by the foregoing description 45 or the accompanying illustration.

Having thus described my invention, I claim:

1. In a printing press, a reciprocable form carrier, means for effecting reversal of the movement of the form carrier at the ends of its strokes comprising teeth on the form carrier, a gear meshing with said teeth, a rack adapted to mesh with said gear, means for reciprocating said rack a plurality of times for each reciprocation of the form carrier, and means whereby said rack is caused to move transversely into and out of mesh with said gear at the beginning and end of each reversal period.

2. In a flat bed printing press, a reciprocating bed, means for effecting reversal of bed movement 60 at the ends of its travel, comprising a rack on the bed, a gear meshing with said rack, a second rack adapted to mesh with said gear, means for reciprocating said second rack a plurality of times for each reciprocation of the bed, and means whereby 65 said second rack is caused to move transversely into and out of mesh with said gear at the beginning and end of each reversal period.

3. In a printing press, a reciprocable form carrier having intermediate periods of constant speed 70 travel, means for effecting reversal of the movement of the form carrier at the ends of its strokes comprising teeth on the form carrier, a gear meshing with said teeth, a cross head, means for reciprocating said cross head a plurality of times 75

for each reciprocation of the form carrier, a rack pivoted to the cross head and adapted to mesh with said gear, and means timed with the reciprocation of said rack for swinging the latter on its pivot in such manner that it is caused to move into mesh with said gear at the end of each constant speed travel and out of mesh at the beginning of the next succeeding constant speed travel.

4. In a printing press, a reciprocable form carrier having intermediate periods of constant speed travel, means for effecting reversal of the movement of the form carrier at the ends of its strokes comprising a gear operatively connected with the form carrier, a cross head, means for reciprocating said cross head with simple harmonic motion three times for each reciprocation of the form carrier, the end of each stroke of the form carrier being timed to correspond with the end of a stroke of the cross head, a rack pivoted to the cross head and adapted to mesh with said gear, and means for swinging the rack on its pivot in such manner that it is caused to move into mesh with said gear at the end of each constant speed travel of the form carrier and out of mesh at the beginning of the next succeeding constant speed travel.

5. In a printing press, a reciprocable form carrier having intermediate periods of constant speed travel, means for effecting reversal of the movement of the form carrier at the ends of its strokes comprising a gear operatively connected with the form carrier, a cross head, means for reciprocating said cross head a plurality of times for each reciprocation of the form carrier, a rack pivoted to the cross head and adapted to mesh with said gear, a support for said rack, and means for moving said support to swing the rack on its pivot in such manner that it is caused to move into mesh with said gear at the end of each constant speed travel of the form carrier and out of mesh at the beginning of the next succeeding constant speed travel of the form carrier.

6. In a printing press, a reciprocable form carrier, means for effecting reversal of the movement of the form carrier at the ends of its strokes comprising a gear operatively connected with the form carrier, a cross head, means for reciprocating said cross head with simple harmonic motion three times for each reciprocation of the form carrier, the end of each stroke of the form carrier being timed to correspond with the end of a stroke of the cross head in the opposite direction, a rack pivoted to the cross head and adapted to mesh with said gear, a support for said rack, and means actuated twice for each reciprocation of the form carrier for moving said support to swing said rack about its pivot into mesh with said gear and to withdraw said support permitting said rack to swing away from mesh with said gear.

60 7. In mechanism of the class described, the combination with a reciprocating bed, of means for actuating said bed throughout its cycle of movement, said cycle comprising intermediate constant speed periods and two reversal periods, said means comprising a reciprocable rack, means for reciprocating said rack, gearing between said rack and said bed effective during reversal to actuate said bed upon reciprocation of said rack, and means for causing said rack to be displaced transversely to its pitch line for disengagement from said gearing during the constant speed periods of the cycle of said bed.

75 8. In mechanism of the class described, the combination with a reciprocating bed, of means for actuating said bed throughout its cycle of

movement, said means comprising a reciprocable rack, means for reciprocating said rack, gearing between said rack and said bed effective to reverse the direction of movement of said bed upon reciprocation of said rack, and means whereby said reciprocating rack is caused to move transversely to its pitch line toward said gearing for engagement therewith during the reversal of the direction of movement of the bed and away from said gearing for disengagement therefrom during the intermediate travel of the bed.

9. In mechanism of the class described, the combination with a reciprocating bed, of means for actuating said bed throughout its cycle of movement, said means comprising a rotatable gear operable to reverse the direction of movement of said bed, a reciprocable rack adapted to mesh with said gear, means for reciprocating said rack, connections between said means and said rack permitting displacement of the latter toward and away from said gear in a direction transverse to the pitch line of said rack, and means effective near both ends of the bed travel for moving said rack into mesh with said gear.

10. In mechanism of the class described, the combination with a reciprocating bed, of means for imparting intermediate constant speed travel to the bed in opposite directions and for reversing the direction of movement of the bed at the ends of its constant speed travel, said means comprising a gear for actuating the bed during the reversal thereof, a reciprocable rack adapted to mesh with said gear, means for reciprocating said rack, connections between said last named means and said rack permitting displacement of the latter toward and away from said gear in a direction transverse to the pitch line of said rack, and means effective near both ends of the bed travel for moving said rack into mesh with said gear.

11. In mechanism of the class described, the combination with a reciprocating bed, of means for actuating said bed throughout its cycle of movement, said means comprising rack teeth carried by said bed, a rotatable gear arranged to mesh with said rack teeth, a reciprocable rack adapted to mesh with said gear, means for reciprocating said rack, and means whereby said rack is caused to move transversely to its pitch line toward said gear for engagement therewith during the end portions of the stroke of the bed and away from said gear for disengagement therewith during the medial portion of the stroke of the bed.

12. In mechanism of the class described, a reciprocating bed, a shaft, mechanism associated therewith for driving said bed at constant speed through the medial portion of its stroke, said mechanism comprising means for driving said shaft in alternately opposite directions, means for reversing the direction of movement of said bed at the ends of its stroke comprising a first rack carried by said bed, a gear mounted on said shaft and continuously in mesh with said first rack, a second reciprocable rack adapted to mesh with said gear, means for imparting substantially harmonic reciprocation to said second rack, and means whereby said second rack is caused to move toward and away from said gear in a direction transverse to the pitch line of said rack to effect engagement with said gear during the two reversal periods only.

13. In mechanism of the class described, a reciprocating bed, means for reciprocating said bed through the medial portion of its stroke com-

- prising a first rack carried by said bed and a gear continuously in mesh with said first rack, and means for reversing the direction of movement of the bed at the ends of its stroke comprising a second reciprocable rack, means for reciprocating said second rack, and means whereby said second rack is caused to move transversely to its pitch line into mesh with said gear during the reversal periods and out of mesh therewith during the medial portion of the stroke.
14. In mechanism of the class described, the combination with a reciprocating bed, of means for actuating said bed throughout its cycle of movement, said means comprising a rotatable gear operatively connected with said bed throughout the cycle of the latter, a reciprocating member for actuating said bed during the reversal of the movement thereof at both ends of the stroke, a rack pivotally connected to said reciprocating member and adapted to mesh with said gear, and means whereby said rack is caused to move about its pivot transversely to its pitch line to bring said rack into engagement with said rotatable gear during the two reversal periods only.
15. In mechanism of the class described, the combination with a reciprocating bed, of means for imparting intermediate constant speed travel to said bed in opposite directions and for imparting substantially harmonic reversing motion to said bed at the ends of its stroke, said means comprising a rotatable gear operatively connected to said bed throughout the cycle of the latter, a Scotch yoke, a rack pivotally connected to said Scotch yoke for reciprocation thereby, said rack being adapted to mesh with said gear, and means whereby said rack is caused to move about its pivot transversely to its pitch line to bring said rack into engagement with said gear during both reversal periods, and out of engagement during the intermediate constant speed travel.
16. In a printing press, a reciprocable form carrier, means for effecting reversal of the movement of the form carrier at the ends of its strokes comprising a gear, a rack adapted to mesh with said gear, means for reciprocating said rack a plurality of times for each reciprocation of the form carrier, and means whereby said rack is caused to move transversely into and out of mesh with said gear at the beginning and end respectively of each reversal period, said form carrier being operatively connected with said gear so as to be reversed thereby.
17. In a flat bed printing press, a reciprocating bed, means for effecting reversal of bed movement at the ends of its travel, comprising a rack on the bed, a gear, a second rack adapted to mesh with said gear, means for reciprocating said second rack a plurality of times for each reciprocation of the bed, and means whereby said second rack is caused to move transversely into and

out of mesh with said gear at the beginning and end of each reversal period, said gear and bed rack being operatively connected.

18. In a printing press, a reciprocable form carrier having intermediate periods of constant speed travel, means for effecting reversal of the movement of the form carrier at the ends of its strokes, comprising a gear, a cross head, means for reciprocating said cross head a plurality of times for each reciprocation of the form carrier, a rack pivoted to the cross head and adapted to mesh with said gear, and means timed with the reciprocation of said rack for swinging the latter on its pivot in such manner that it is caused to move into mesh with said gear at the end of each constant speed travel and out of mesh at the beginning of the next succeeding constant speed travel, said form carrier being operatively connected with said gear so as to be reversed thereby.

19. In a printing press, a reciprocable form carrier, means for effecting reversal of movement of the form carrier at the ends of its strokes, comprising a gear, a rack adapted to mesh with said gear, means for reciprocating said rack an odd number of times greater than one for each reciprocation of the form carrier, and means whereby said rack is caused to move transversely into and out of mesh with said gear at the beginning and end of each reversal period.

20. In a flat bed printing press, a reciprocating bed, means for effecting reversal of bed movement at the ends of its travel, comprising a rack on the bed, a gear, a second rack adapted to mesh with said gear, means for reciprocating said second rack an odd number of times greater than one for each reciprocation of the bed, and means whereby said second rack is caused to move transversely into and out of mesh with said gear at the beginning and end of each reversal period.

21. In a printing press, a reciprocable form carrier having intermediate periods of constant speed travel, means for effecting reversal of movement of the form carrier at the ends of its strokes comprising a gear, a cross head, means for reciprocating said cross head an odd number of times greater than one for each reciprocation of the form carrier, a rack pivoted to the cross head and adapted to mesh with said gear, means timed with the reciprocation of said rack for swinging the latter on its pivot in such manner that it is caused to move into mesh with said gear as it travels outwardly at the end of each constant speed travel of the bed, and out of mesh as it travels inwardly at the beginning of the next succeeding constant speed travel of the bed.
